MANUFACTURE OF CIGARETTES

Rowland Frank May, Middlesex, England, assignor to Filter Tips Limited, London, England, a British company

Application October 31, 1934, Serial No. 750,906
In Great Britain July 14, 1933

2 Claims. (Cl. 131—39)

This invention relates to the manufacture of cigarettes having filter tips or like stub portions.

The invention has for its primary object to provide an improved method of and means for producing such cigarettes by the application of filter tips or like stub portions to cigarettes as produced, for example, on the continuous rod machine.

10 According to the present invention, cigarettes having filter tips or like stub portions are produced by a method which consists in providing a cigarette with a tubular mouthpiece formed by the application of a band of paper, cork or the like and thereafter inserting a filter tip or equivalent stub portion into the tubular mouthpiece.

According to the invention, moreover, apparatus for carrying out the method specified comprises intermittently movable carrying means having chambers for receiving and holding cigarettes, means for applying strips of paper, cork or the like to the cigarettes in such manner as to provide tubular mouthpieces extending from the ends of the cigarettes, and means for inserting filter tips or like stub portions into the tubular mouthpieces so formed. In one embodiment the intermittently movable carrying means may be provided with rotatable sleeves for the reception of the cigarettes, means being provided for rotating the said sleeves either during the intermittent movement of the carrier or during its periods of rest for the purpose of wrapping the bands of paper, cork or the like around the ends of the cigarettes. Alternatively, the sleeves or equivalent cigarette-receiving means may be non-rotatable in relation to the carrying means and the bands of paper, cork or the like may be applied by means such as a roller or group of rollers or the equivalent rotatable in relation to the cigarettes. The sleeves may be provided with gripping means such as springs for holding the cigarettes in position in the sleeves and for preventing the rotation of the cigarettes in relation to the sleeves.

The cigarettes may be fed to the intermittently movable carrying means from the continuous rod machine and in order to allow for sufficient time interval for the application of the bands of paper, cork or the like, two intermittently movable carriers may be provided and the cigarettes may be fed alternately to the carriers by means of an oscillatable member having two parallel chambers or bores therein. Conveniently, the intermittently movable carrying

means comprises an intermittently rotatable drum.

The invention is hereinafter described by way of example with reference to the accompanying diagrammatic drawing, in which:—

Figure 1 is an end elevation partly in section illustrating one embodiment of apparatus according to the invention;

Figure 2 is a sectional plan view on the line II—II Figure 1; and

Figure 3 is a sectional plan view on the line III—III, Figure 1.

In carrying the invention into effect and with reference to the accompanying diagrammatic drawing, cigarettes are fed into sleeves 1a in an intermittently rotatable drum 1, either from a hopper or preferably from a continuous rod machine, and the cigarettes are held in such sleeves 1a so that one end of the cigarette 2 projects therefrom for the application of an encircling band 3 of paper, cork or the like previously coated with adhesive, the device 4 by which the band 3 is wrapped around the cigarette being arranged so that the band 3 provides a tubular mouthpiece projecting beyond the end of the cigarette 2, as shown in Figure 3. The wrapping of the band 3 around the cigarette 2 conveniently is effected by rotating the sleeve 1a in relation to the drum 1 either during movement of the drum from one stage to another, or during the period at which the drum is at rest. For instance, the rotatable sleeves 1a holding the cigarettes may be caused to rotate by the co-operation of gear wheels 1b on the sleeves 1a with a fixed rack or with a movable rack or segmental gear wheel according to whether the rotation is to be effected while the drum is moving or while it is stationary. Springs 1c or other gripping means may be provided for the purpose of holding the cigarettes against displacement in the sleeves 1a. The band 3 of paper, cork or the like is fed into the device 4 through a tangential slot 4a by means of rollers 8 and a guide 9.

In a preferred arrangement, as shown in the drawing, the cigarettes are fed alternately, from a guide 7 leading from a continuous rod machine, to a pair of drums 1 by means of an oscillatable member 5 provided with two parallel bores 5a or chambers from which the cigarettes are ejected into the respective sleeves 1a by means of plungers 6, 6a. Such an arrangement provides for sufficient time interval while the drums are stationary for the effective application of the bands 3.

The filter tips 10 or equivalent stub portions may be inserted from any suitable forming mech-

anism 11 or from an intermediate carrier or magazine into the tubular mouthpieces formed by wrapping the bands 3 around the end portions of the cigarettes. In order to facilitate the introduction of the filter tips or stub portions, the bore in each device 4 may be formed with a shoulder 4b against which the end of the cigarette 2 abuts so that the filter tip 10 or like stub portion may be inserted without any possibility of fouling the mouthpiece. The cigarettes 10 advantageously are fed from the continuous rod machine in such manner that the seam of a cigarette paper case is in definite relation to the mechanism for applying the bands 3 so that the 15 seam of the tubular mouthpiece will be always in alignment with the seam of the cigarette paper case or in definite relation thereto.

In a modification, the intermittently movable carrying means, such as the drum 1, may be provided with sleeves or equivalent cigarette-receiving means non-rotatable in relation thereto and each band of paper, cork or the like is applied by means such as a roller or group of rollers or the equivalent rotatable about the axis 20 of the cigarette. A band of paper, cork or the like fed between the projecting part of a cigarette and the aforesaid roller or group of rollers or the equivalent may, by the rotation of the same about the axis of the cigarette, be thereby wrapped 25 around the latter.

30

It will be understood that the invention is not limited to the particular details hereinbefore described. For example, in place of a drum, any suitable intermittently movable carrier, such as an endless chain, may be utilized and the wrapping of the band of paper, cork or the like around the cigarette to form the tubular mouthpiece may be effected by other suitable means.

What I claim is:—

1. A method of producing filter tip cigarettes 10 comprising positioning a cigarette in a retaining chamber, wrapping a strip of material around one end to form a tubular mouthpiece, and before ejection of the cigarette from the chamber inserting a filter plug in said mouthpiece with 15 one end of said plug abutting the tobacco of the cigarette and the other end of said plug flush with the free end of the mouthpiece tube.

2. A method of producing filter tip cigarettes 20 comprising positioning a cigarette in a retaining chamber, rotating the cigarette while applying a strip of mouthpiece material to one end of the cigarette to form a tubular mouthpiece, and inserting a filter plug in said mouthpiece with one 25 end of said plug abutting the tobacco in the cigarette and the free end of the plug flush with the free end of the tubular mouthpiece before removal of the cigarette from said chamber.

ROWLAND FRANK MAY.
